US00D915438S

(12) **United States Design Patent** (10) Patent No.: **US D915,438 S**
(45) Date of Patent: ** Apr. 6, 2021

(54) **DISPLAY SCREEN OR PORTION THEREOF WITH GRAPHICAL USER INTERFACE**

(71) Applicant: **Lutron Technology Company LLC**, Coopersburg, PA (US)

(72) Inventors: **Erica L. Clymer**, Northampton, PA (US); **Benjamin F. Bard**, Zionsville, PA (US); **Jennifer Wong**, Breinigsville, PA (US); **Joel Hnatow**, Allentown, PA (US)

(73) Assignee: **Lutron Technology Company LLC**, Coopersburg, PA (US)

(**) Term: **15 Years**

(21) Appl. No.: **29/689,872**

(22) Filed: **May 2, 2019**

Related U.S. Application Data

(63) Continuation of application No. 29/601,123, filed on Apr. 19, 2017, now Pat. No. Des. 849,050, which is a continuation of application No. 29/531,293, filed on Jun. 24, 2015, now Pat. No. Des. 791,827.

(57) **CLAIM**

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof and form no part of the claimed design.

1 Claim, 1 Drawing Sheet
